ATTORNEY.

UNITED STATES PATENT OFFICE

130,139

DESIGN FOR A FOOD GRATER

Irving Rosenbloom, New York, N. Y.

Application August 14, 1941, Serial No. 102,843

Term of patent 7 years

To all whom it may concern:

Be it known that I, Irving Rosenbloom, a citizen of the United States of America, residing in New York city, county of New York, and State of New York, have invented a new, original, and ornamental Design for a Food Grater, of which the following is a specification, reference being had to the accompanying drawing, forming part thereof.

Fig. 1 is a front perspective view of a food grater, showing my new design.

Fig. 2 is a rear perspective view thereof.

I claim:

The ornamental design for a food grater, substantially as shown.

IRVING ROSENBLOOM.
